UNITED STATES PATENT OFFICE.

JAMES T. SMITH, OF NEWARK, NEW JERSEY.

TABLE FOR SETTING OUT LEATHER.

1,003,529.

Specification of Letters Patent. Patented Sept. 19, 1911.

Application filed July 15, 1910. Serial No. 572,104.

To all whom it may concern:

Be it known that I, JAMES T. SMITH, a citizen of the United States, residing at Newark, in the county of Essex and State of New Jersey, have invented certain Improvements in Tables for Setting Out Leather, of which the following is a specification.

The objects of this invention are to provide a suitable and convenient table for setting out leather according to the method set forth in my prior application Serial No. 512,312, filed August 11, 1909; to enable the workmen to work at said table from either side of the same; to this end to provide a table which can be tilted upon a median horizontal axis; to enable the table to be locked in any desired angular position; to avoid bringing the setting-out board with the leather applied thereto into such positions, when off the table, that gravity will tend to separate them; to thus reduce to a minimum the tendency of the leather to separate from the setting-out board while wet and heavy, and to obtain other advantages and results as may be brought out in the following description.

Referring to the accompanying drawings, in which like numerals of reference indicate corresponding parts in each of the several figures, Figure 1 is a side elevation of my improved table with a setting-out board and piece of leather thereon, looking at the edge of the table away from the operators during the first part of the setting-out operation; Fig. 2 is an end view of the same; Fig. 3 is a cross section of the table and setting-out board, taken on line A—A of Fig. 1, looking in the direction indicated by the arrow, showing in dotted lines the setting-out board removed from the table at the end of the first part of the operation, and in full lines the table with said setting-out board placed back upon it for the last part of the operation, and Fig. 4 shows the table, still in section on line A—A of Fig. 1, restored to inclined position for setting-out the second half of the piece of leather.

In said drawing, 1 indicates a table top providing a hard, smooth upper surface 2 upon which the setting-out board 3 can be laid flatwise either with a piece of leather set out upon itself or without. Said table top 1 I have shown secured in fixed position upon a beam 4 which extends longitudinally

along the middle of the table. Posts 5 project downward from the under side of said beam 4, and from opposite sides of the lower end of each of these posts braces 6, 6 extend upwardly to the opposite outer edges of the table top 1. Obviously there can be as many sets of posts 5 and braces 6, 6 as the length of the table renders necessary to rigidly and firmly support the table top. It should be noted that said posts 5 and braces 6, 6 do not reach to the floor, however.

The ends of the beam 4 are rounded, as at 7, to form trunnions, and are journaled in bearings 8 provided at the upper parts of standards 9 of any suitable and stable construction. Said bearings 8 are provided with caps 10 bolted thereto, as at 11. The table is thus adapted to rock upon the trunnions 7, 7 to bring the table top 1 into any angular position desired. Suitable means are furthermore provided for locking the table in different angular positions, those shown in the drawing consisting of a collar 12 upon each of the trunnions 7, 7 outside of the bearings 8, 8, said collar being keyed to the trunnions, as at 13. Said collar has a peripheral series of radially disposed sockets 14, and a pin 15 extending through a seat or aperture in an arm 16 projecting from the cap 10 out over said collar 12 is adapted to be inserted into any one of said series of sockets 14 to hold the table against turning. Preferably there are two of these locking means, one at each end of the table, so as to secure said table firmly in a desired position. Other suitable means adapted to the purpose could be employed for holding the table against rocking or tipping, and the table could be supported in other ways equivalent to the one shown, without departing from the spirit and scope of my invention. The detail construction of the table itself could also be varied as mechanical skill might suggest, so long as there is provided a flat top 2 which can be tipped into different angular positions.

The table top 2 preferably has adjacent to each of its long side edges sockets 17, 17 and 18, 18 adapted to receive pins 19, 19. Each pair of these sockets is placed at such a distance from the near edge of the table top that the setting-out board 3 resting at one of its edges against the pins 18 in said sockets will be substantially flush at its other edge with the far edge of the table.

In operation, the table is locked in such position that its top inclines away from the operators downwardly, the pins 19 are placed in the holes or sockets 17 farthest 5 from the operators, and the setting-out board 3 is laid upon the table top at its edge away from the operators against the pins 19. The first half 20 of the piece of leather 21 is then brought upon the setting-out board 3 and set-out and stretched thereon according to the method set forth in my said prior application Serial No. 512,312, filed Aug. 11, 1909, or the modification thereof described in my application Ser. No. 538,668, filed January 18, 1910. When the setting-out of the first half 20 of the leather is completed, the setting-out board 3 with the leather thereupon is slid off of the table, preferably by the two men taking hold of 20 said board at its opposite ends, and is held in horizontal position, as shown in Fig. 3 of the drawing, while the table is tipped in the same direction until its top 1 is substantially vertical, as shown in said Fig. 3. The pins 25 19 are then changed from the holes or sockets 17, 17 to the sockets 18, 18 at the lower edge of the table top, and the near edge of the setting-out board or edge next the table being brought to rest upon said pins 19, said 30 setting-out board is tilted into vertical position so that its side having the half 20 of the leather thereon rests flatwise against the table top, whereupon the other half 22 of the piece of leather falls against the opposite side of the setting-out board, all as 35 clearly shown in Fig. 3 of the drawing. The table is then tilted or swung into the same angular relation to the horizontal as it was at the commencement of the operation, except that the edge which was lowest then is highest now and the operators work from the opposite side of the table from that which they did in setting-out the first half 20 of the piece of leather. When the workmen 40 have finished setting-out said second half 22 of the piece of leather, the table is again tipped into vertical position, as shown in Fig. 3, and with one man at each end the setting-out board with the leather set-out 45 thereupon is lifted off, and still being kept in vertical edgewise position is carried away for drying or subsequent operations.

The process of setting out leather, in which the table forming the subject of this

application is employed, is set forth and 55 claimed in my allowed application Serial No. 568,972, filed June 27, 1910.

Having thus described the invention, what I claim is:

1. The herein-described table for setting-out leather, comprising a top presenting a flat upper surface, trunnions at the opposite ends of said table in the median longitudinal line thereof, supports providing bearings for said trunnions, means for locking said table in different angular positions, and stops adapted to project upward from said flat upper surface of the table top and to be removed therefrom.

2. The herein-described table for setting-out leather, comprising a top presenting a flat upper surface, means for pivotally supporting said top along the longitudinal median line thereof, and stops projecting from said upper flat surface of the table top 75 adapted to be shifted thereon.

3. The herein-described table for setting-out leather, comprising a top presenting a flat upper surface with sockets therein adjacent to each side edge; means for pivotally 80 supporting said table top along the longitudinal median line thereof, and stops adapted to be inserted in said sockets.

4. The herein-described table for setting-out leather, comprising a top presenting a 85 flat upper surface, means for supporting said table top so that its said flat upper surface can be brought into substantially vertical plane and inclined in either direction to the horizontal, and stops projecting from 90 said flat upper surface near one side edge of the table top.

5. The herein-described table for setting-out leather, comprising a top presenting a flat upper surface, means for pivotally supporting said top along the longitudinal median line thereof, means for holding said 95 table top against tipping in certain angular positions, and removable stops adapted to be stationed on said table top at either longitudinal margin thereof and project upward from the plane of the flat upper surface of said top.

JAMES T. SMITH.

In the presence of—

RUSSELL M. EVERETT,
FRANCES E. BLODGETT.
